(57) **CLAIM**

The ornamental design for a weight scale, as shown and described.

DESCRIPTION

FIG. 1 is a front perspective view of a weight scale according to the present invention;

FIG. 2 is a rear perspective view thereof;

FIG. 3 is a front elevation view thereof;

FIG. 4 is a rear elevation view thereof;

FIG. 5 is a left side view thereof, the right side view being mirror image thereof;

FIG. 6 is a top plan view thereof;

FIG. 7 is a bottom plan view thereof;

FIG. 8 is a fragmentary cross-sectional view taken along lines **8-8** of FIG. 3;

FIG. 9 is an enlarged view of an area circumscribed in FIG. 1;

FIG. 10 is an enlarged view of an area circumscribed in FIG. 5; and,

FIG. 11 is an enlarged view of an area circumscribed in FIG. 8.

The dot-dash-dot broken lines in FIG. 3 depict the cross-sectional cut lines that form no part of the claimed design. The broken lines in FIGS. 1, 5, 8 and 9-11 depict boundaries of enlargements of a weight scale that form no part of the claimed design. The even-space broken lines in FIGS. 2, 6, 8 and 11 depict the portions that form no part of the claimed design.

1 Claim, 11 Drawing Sheets
